US0D1066485S

(12) **United States Design Patent** (10) **Patent No.:** **US D1,066,485 S**
(45) **Date of Patent:** **** Mar. 11, 2025**

(54) **LABEL**

(71) Applicant: **CCL Label, Inc.**, Framingham, MA (US)

(72) Inventors: **Jay Sato**, Mission Viejo, CA (US); **Laura Cruz**, Placentia, CA (US); **Jenifer Do**, Fullerton, CA (US)

(73) Assignee: **CCL Label, Inc.**, Framingham, MA (US)

(**) Term: **15 Years**

(21) Appl. No.: **29/899,931**

(22) Filed: **Aug. 15, 2023**

Related U.S. Application Data
